REFINING LUBRICATING OIL WITH DI-CHLOROETHYL ETHER

Clifford C. Buchler and James M. Page, Jr., Casper, Wyo., assignors to Standard Oil Company, Chicago, Ill., a corporation of Indiana

Application March 10, 1932, Serial No. 597,890

15 Claims. (Cl. 196—19)

This invention relates to refining lubricating oils and it pertains more particularly to the dewaxing and extraction thereof with dichlorethyl ether.

5 The object of the invention is to provide a method of dewaxing lubricating oil by means of a selective solvent which will dissolve practically all of the oil and which will not dissolve the petroleum waxes contained therein. A further 10 object is to provide a combined treatment of petroleum oil with dichlorethyl ether so that the wax may be removed from the oil prior to the separation of paraffinic from naphthenic components. A further object is to provide an improved 15 system whereby a blending agent may be mixed with dichlorethyl ether to effect complete solution of the oil during the dewaxing treatment and whereby this blending agent may be distilled from the diluted oil to cause the separation of 20 paraffinic oil from the dichlorethyl ether solution. A further object is to decrease the cost of separating undesirable components from a lubricating oil and to provide a lubricating oil of improved properties.

25 In practicing the invention we utilize a solvent, such as B. B' dichlorethyl ether,

30 This dichlorethyl ether is completely miscible with both oil and wax at temperatures of from 125°-165° F., depending upon the molecular weights of the oil and wax. When this mixture is cooled to about 100° F., the waxes are precipitated from the solution while the bulk of the 35 oil remains in the solution and a separation may therefore be effected. Our preferred method, however, is to dewax at temperatures below 0° F., and in order that the oil may remain in solution at these low temperatures we mix benzene with 40 the dichlorethyl ether. When the benzene is removed from the dewaxed oil the paraffinic and naphthenic components thereof may be readily separated by the dichlorethyl ether which remains admixed therewith.

45 The invention will be more clearly understood from the following detailed description and from the accompanying drawing which illustrates a preferred embodiment of our invention. The drawing represents a diagrammatic plan of our 50 improved system. We may utilize our invention in treating any wax-bearing oil, but in our preferred embodiment we will describe the method of dewaxing and extracting a Salt Creek motor base which has been treated with 2½ pounds of 55 104½% sulfuric acid, said oil having a viscosity

of about 75-78 seconds Saybolt at 210° F. When heavy oils are used it may be desirable to cut their viscosity by means of filter naphtha or other light hydrocarbon diluent. In such case, the diluent may be considered as a part of the oil undergoing treatment.

5 The oil from storage tank 10 may be withdrawn through pipe 11 to mixer 12, where it is admixed with benzene from storage tank 13, pipe 14 and pipe 15, and dichlorethyl ether from tank 16, pipe 17 and pipe 18. We prefer to use about two and one-half parts of dichlorethyl ether to one part of oil and enough benzene to keep the oil in solution at the dewaxing temperature. These ingredients are thoroughly mixed in mixer 12 and introduced by pipe 18 to chiller 19. The chiller may contain any suitable heat exchange cooling apparatus such as coil 19a, and it may be provided with suitable scrapers for removing the deposited wax from cool surfaces. On the 20 other hand, the refrigeration may be accomplished by the vaporization of a diluent or refrigerant directly from the liquid in the chamber. The cooling rate may be about 5° per hour, if ordinary brine cooling coils are used, but if the 25 refrigeration is accomplished by the direct vaporization of propane or equivalent means it may be as high as two or three degrees per minute.

30 The slurry from the chill chamber is introduced by pipe 20 to a suitable wax filter 21, wax cake being removed therefrom through enlarged conduit 22 and the filtrate being withdrawn through pipe 23 to collecting tank 24. The filter may be of any desired type, but we preferably use a plurality of vertical filters of the type disclosed in U. S. Patent No. 869,372. While a cake is being built up in one filter the cake in another filter will be washed, and the cake in a third filter will be removed. This particular feature 35 forms no part of the present invention and it will not be described in detail.

40 Dewaxed oil, together with the benzene and dichlorethyl ether, is introduced from the filtrate collector 24 through pipe 25 and heat exchanger 26 to benzene still 27, which is heated by suitable steam coil 28. The benzene vapors are removed through pipe 29, condensed in condenser 30 and returned to storage tank 13. The hot mixture of dichlorethyl ether and oil is removed from the 45 base of the benzene still through pipe 31, and it is cooled in exchanger 26 to about 40° F., at which temperature it is introduced into extraction tank 32. At this temperature the paraffinic components of the oil are insoluble in the dichlor-

ethyl ether, and these two liquids may be separated by decantation, centrifuging or other suitable mechanical means. For instance, the paraffinic oil may be withdrawn from the top of the 5 ether solution through one of the pipes 33 and header 34,—the dichlorethyl ether solution being withdrawn through pipe 35 and heat exchanger 36 to dichlorethyl ether still 37. The liquid in this still is heated by steam coil 38, the solvent 10 being returned through pipe 39 and condenser 40 to storage tank 16, and the naphthenic constituents of the oils being withdrawn through pipe 41 and heat exchanger 36.

Using 30% dichlorethyl ether and 70% benzene, and using about 3 parts of the oil to 7 parts of this diluent at a dewaxing temperature of 0° F. we obtained good wax separation and good filter rates. In this case, however, it was found desirable to add further amounts of the dichlor- 15 ethyl ether prior to the extraction step, or to repeat the extraction with one or more additional dumps of dichlorethyl ether.

It should be understood that we may use other chlorinated oxygen-containing compounds, particularly chlorinated ethers, instead of B.B' dichlorethyl ether, in practicing our invention, and we may use other blending or miscibility agents than benzene, such as acetone, toluene, etc. Of course, if a blending agent, such as toluene or 20 xylene, is used which has approximately the same boiling point as the dichlorethyl ether, it will be necessary to remove all of the diluent from the oil prior to the extraction of the naphthenic constituents. We therefore prefer to use a lower 25 boiling blending agent, such as benzene, so that it may be fractionally removed from the diluted oil prior to the extraction step. A preferred mixture is 30% dichlorethyl ether and 70% benzene.

Filter rates may be increased by the use of 30 other diluents, such as light hydrocarbons like butane or propane, and, if necessary, filter aids such as infusorial or diatomaceous earth may be employed.

It should be understood that the amount of 45 dichlorethyl ether, blending agent and/or other diluents may be varied throughout a relatively large range, depending upon the specific oil which is to undergo treatment. The blending agent may be omitted entirely and the wax may 50 be separated from the diluted oil in liquid form by decantation or in solid form by filtration or centrifuging. It may be readily ascertained by experiment just how much benzene is required to hold the oil in solution at any given temperature and at the same time keeping the wax out 55 of solution.

While we have described in detail a preferred embodiment of our invention it is to be understood that we do not limit ourselves thereto except as defined by the following claims, which should be construed as broadly as the prior art will permit.

We claim:

1. The method of dewaxing a wax-bearing lubricating oil which comprises intimately admixing said oil with dichlorethyl ether, cooling said mixture to effect separation of wax from the oil-dichlorethyl ether mixture, mechanically removing said wax from said mixture, and removing 65 the dichlorethyl ether from the dewaxed oil.

2. The method of dewaxing lubricating oil which comprises diluting said oil with a mixture of dichlorethyl ether and a non-paraffinic blending agent in such proportion to each other and 70 to the oil that at diluting temperature both oil

and wax are soluble in the solvent mixture and that at dewaxing temperature the wax is substantially insoluble and the oil is completely soluble, cooling the mixture to crystallize the 5 wax, mechanically removing the diluted oil from the crystallized wax and removing the blending agent and dichlorethyl ether from said dewaxed oil.

3. The combination of claim 2 wherein the blending agent is benzene.

4. In the process of separating petroleum oils into fractions of different degrees of paraffinicity by means of the selective solvent action of dichlorethyl ether, the method of regulating the amount of oil which can be dissolved in the 15 dichlorethyl ether at low temperatures, which comprises mixing said oil and dichlorethyl ether with a non-paraffinic blending agent in which the oil is soluble at dewaxing temperatures.

5. The method of claim 4 wherein the blending 20 agent is benzol.

6. The method of refining a wax-bearing petroleum oil comprising both naphthenic and paraffinic components, which comprises diluting said oil with dichlorethyl ether and a non-paraffinic blending agent in which the oil is soluble at dewaxing temperatures, chilling the mixture to effect solidification of the wax, mechanically separating the solidified wax from the diluted oil, effecting phase separation between paraffinic 30 and naphthenic components of the wax-free diluted oil by removing at least a part of the blending agent and subsequently cooling to effect the separation of a paraffinic phase from a naphthenic phase, removing one phase from the other, 35 and finally removing the dichlorethyl ether and blending agent from both the paraffinic and naphthenic components.

7. The method of refining a wax-bearing petroleum oil comprising both naphthenic and paraffinic components, which comprises diluting said oil with dichlorethyl ether and a non-paraffinic blending agent in which the oil is soluble at dewaxing temperatures, chilling the mixture to effect solidification of the wax, mechanically separating the solidified wax from the diluted oil, heating said diluted oil to remove at least a portion of the blending agent, chilling the heated oil to effect a separation of naphthenic from paraffinic components of the oil, removing the 50 paraffinic from the naphthenic components, and finally removing the dichlorethyl ether from both components.

8. The method of claim 7 wherein the blending agent is benzol.

9. The method of claim 7 wherein the diluent which has been heated to remove at least a portion of the blending agent is cooled for the phase separation by indirect heat exchange with cold 60 diluted oil from the wax separation step.

10. The method of claim 1 wherein the wax-bearing lubricating oil is diluted with a paraffinic diluent during the wax separation and the wax removal steps.

11. The method of claim 2 wherein the oil is 65 admixed with a light non-viscous paraffinic diluent during the wax crystallization and wax removal steps.

12. The method of claim 1 wherein the lubricating oil contains paraffinic and naphthenic components as well as wax and wherein the paraffinic components are separated from said naphthenic components by said dichlorethyl ether.

13. The method of claim 2 wherein the lubricating oil contains paraffinic and naphthenic com-

ponents as well as wax and wherein the paraffinic and naphthenic components are separated by means of said dichlorethyl ether.

14. The process of manufacturing high viscosity index lubricating oil having a low pour test from wax-bearing mineral oil which comprises mixing with the oil a solvent liquid mixture composed of dichlorethyl ether and a modifying solvent liquid having substantially no selective action as between constituents of the oil of differing viscosity indices, and mixed with each other and with the oil in proportions such that at temperatures of around 0° F. the mixture has substantially complete solvent action on the oil, and substantially

no solvent action on the wax, chilling the mixture to precipitate wax constituents of the oil, removing the wax thus precipitated, removing from the resulting dewaxed mixture a suitable portion of the modifying solvent to thereby render the remaining solvent liquid selective as between constituents of the oil of differing viscosity index, and separating from the remaining mixture a fraction of desired viscosity index and low pour test. 5

15. A process of dewaxing oils, which comprises incorporating with the oil beta beta-dichloro-diethyl ether, chilling, and separating the wax. 10
